United States Patent Office.

JAMES M. FORD, OF BROOKLYN, NEW YORK.

Letters Patent No. 91,836, dated June 29, 1869.

IMPROVED WINDOW-PULLEY.

The Schedule referred to in these Letters Patent and making part of the same.

To all whom it may concern:

Be it known that I, JAMES M. FORD, of Brooklyn, in the county of Kings, in the State of New York, have invented a new and improved Window-Pulley; and I do hereby declare the following is a full and exact description thereof, reference being made to the accompanying drawings, and to the figures of reference thereon.

The nature of my invention consists in inserting two pulley-wheels, over which the cords sustaining the sash and weight run, in a case of tubular form, to be inserted in the window-sash frame, substantially as hereinabove described.

To enable others skilled in the art to make and use my invention, I will now proceed to describe its construction and operation.

In the accompanying drawings—

Figure 1 is a perspective view of the case containing the pulley-wheels;

Figure 2 is a vertical longitudinal section through the case; and

Figures 3 and 4, are views of the wheels detached from the case.

The case is provided with openings, D D, in its upper side, large enough to insert the wheels, the journals of which have their bearings at b b, in the inside of the case.

These bearings are formed by making cavities C C, in the inner surface of the case, so that the wheels may be dropped in from above; their journals resting in the lower parts of said cavities, at b b.

The case, though tubular in form, is not a complete cylinder, as the upper side must be open, as hereto-

fore mentioned, to allow the wheels to be inserted. It may, however, be completely cylindrical in the centre, with openings on each side, to insert the wheels, or the upper part may be open from end to end, as shown in the drawings.

There are two open slots, f f, in the under side of the cylinder, for the cords to pass through.

The sides of the inner surface of the case, between which the wheels run, are not curved, but flat, forming vertical parallel walls, enclosing the wheels.

B is a face-plate, cast solid with the case, and i, a screw-hole, for attaching the same to the sash-frame by a single screw. I do not limit myself, however, to this particular form of face-plate.

The two wheels, over which the cords run, by increasing the friction, will cause a less weight to balance, or hold the sash suspended, than a single wheel, as commonly used for said purpose.

To insert my pulley, a round hole is made in the sash-frame, by means of an auger, or bit, the tubular case inserted in said hole, and the face-plate attached to the frame.

What I claim as my invention, and desire to secure by Letters Patent, is—

The combination of the tubular case A, and the pulley-wheels c c, inserted therein, the same being constructed substantially as and for the purpose described.

JAMES M. FORD.
